Primary Examiner—B. J. Bullock**Assistant Examiner**—Linda Brooks**Attorney, Agent, or Firm**—Howell & Haferkamp, L.C.**[57] CLAIM**

The ornamental design for a freestanding shoe rack, as shown and described.

DESCRIPTION

FIG. 1 is an orthographic projection of the shoe rack of the present invention;

FIG. 2 is a top plan view of the shoe rack;

FIG. 3 is a bottom plan view of the shoe rack;

FIG. 4 is a front elevation view of the shoe rack;

FIG. 5 is a rear elevation view of the shoe rack;

FIG. 6 is a right side elevation view of the shoe rack, the left side elevation view being a mirror image of the right side elevation view; and,

FIG. 7 is an orthographic projection of the shoe rack in alternate assembly, the difference being the vertical placement of the shoe holding elements.
